UNITED STATES PATENT OFFICE.

RUDOLPH M. KANIK, OF CLINTONVILLE, WISCONSIN.

STEERING MECHANISM.

1,357,327.

Specification of Letters Patent. Patented Nov. 2, 1920.

Application filed April 12, 1920. Serial No. 373,104.

To all whom it may concern:

Be it known that I, RUDOLPH M. KANIK, a citizen of the United States, and resident of Clintonville, in the county of Waupaca and State of Wisconsin, have invented certain new and useful Improvements in Steering Mechanism; and I do hereby declare that the following is a full, clear, and exact description thereof.

10 My invention relates to new and useful improvements in steering mechanism for automobiles, motor vehicles and the like, and pertains particularly to machines of this character having means for driving the 15 steered wheels.

It is the principal object of this invention to provide a simply constructed, readily assembled steering mechanism for four-wheel drive motor vehicles.

20 It is an additional object of the invention to provide a simple steering mechanism in which the moving parts will have very extensive bearing surfaces so that wear and disalignment of parts, which at present frequently occurs, may be entirely eliminated.

25 A further object of the invention is to provide a mechanism of this sort with simply constructed means for positively excluding dust and the like from the inner working 30 parts, such as the end thrust bearings.

Still another object of the invention is to provide a steering mechanism in which the wheel supporting spindle and the bearing 35 pintles are lightly, yet strongly, constructed of a single casting or the like.

With these general objects in view, the invention resides in the novel features of construction, combination and arrangement of parts which will be hereinafter more particularly described and claimed, and shown 40 in the accompanying drawing, wherein:

Figure 1 represents a central vertical longitudinal sectional view through the parts of the vehicle axle structure in which my invention is embodied, such section being taken on the plane of the line 1—1 of Fig. 2, and

Fig. 2 is a vertical transverse sectional view taken substantially on the plane of the line 2—2 of Fig. 1.

50 Referring to the illustrated embodiment of the invention, the reference character 1 denotes one end portion of a drive axle housing which is designed to be attached to the main portion of such housing by a radial flange 2. The housing supports a vertically disposed relatively elongated bearing shell 3,

the inner walls of the outer end portions of which are cylindrical and receive cylindrical bearing pintles 4. The intermediate portion of the shell 3 adjacent its connection with the housing 1 is formed with a spherical enlargement 5 which communicates with the bore of said housing and directly opposite and alined with said bore the same is provided with a circular spindle receiving opening 6.

As shown, this opening 6 is mid-way the opposite ends of the shell 3 which has its top end closed as at 7 by means of a wall formed integrally with the adjacent portion of the cylindrical part of said shell, while the bottom end is open and internally screw threaded as at 8. An adjustable closure plug 9 is adapted to be threaded into the bottom end of the shell. Particularly from Fig. 2 it will be seen that the shell and the housing 1 are split, the former transversely and the latter longitudinally, on a plane extended through the center of the opening 6. Flanges 9 extending from the housing and shell adjacent the walls of the split thereof provide a means for separably securing the two halves together by bolts 10.

By the provision of the two-part housing 1 and shell 3, the pintles 4 may be readily inserted into the opposite ends of said shell, these pintles being extended in opposite directions from a carrying member which is in the form of a one-piece hollow spindle 11, the portion 12 thereof within the shell 3 and 40 from which the pintles extend having an enlarged chamber adapted to receive the universal joint of a drive shaft (not shown). Inasmuch as the spindle 11 is hollow and the pintles 4 are formed integrally therewith, as 45 well as certain parts to be hereinafter mentioned, a very light, compact and strong article is formed.

The outer end portion of the spindle 11 is designed to rotatably support a wheel of 50 a suitable character having a hub 13. Bearing elements 14 are located between the spindle 11 and the wheel hub for an obvious purpose, and the former is also provided with a radial flange 15 which carries packing 16 and is disposed in engagement with the inner end of said hub 13. By extending the 55 hereinbefore referred to drive shaft through the hollow spindle and connecting it with the hub 13, the wheel supported thereby will 60 be readily rotated.

Disposed in each end of the shell 3 is a

bearing plate 17, one of which seats against the top 7 and the other against the inner end of the plug 14. An inwardly projecting bearing stud 18 projects from each of the 5 plates 17 and is disposed in a relatively deep socket 19, located in the outer end of each pintle 4. From Fig. 1 it will be noticed that these sockets 19 are quite deep and thus provide considerable bearing space on their 10 inner walls. Bearing elements 20 coöperate with said annular walls of the sockets 19 and the peripheral surface of the studs 18. Such an arrangement procures very efficient end thrust bearings.

15 The peripheral walls of the pintles 4 are in bearing engagement with the inner surface of the end portions of the shell 3, and inasmuch as these pintles, including the flange formed by the sockets 19, are relatively long, the bearing contact between said 20 pintles and shell is comparatively great. The end thrust bearings when packed with grease are protected against the loss of the lubrication and the entrance of dust and the 25 like by packing rings 21 which are disposed in annular grooves 22 and engaged with the shell wall.

From the foregoing description taken in connection with the accompanying drawing, 30 it will be seen that my invention provides a most simple way of pivotally mounting a wheel supporting spindle and a means for housing a drive shaft therein. By the positioning of the two parts of the shell 3 as 35 hereinbefore described and as shown, there is no danger of any foreign matter leaking into the inner parts of the shell 3 through the top thereof.

I claim:

40 1. In a steering mechanism of the class described, an elongated tubular bearing shell closed at one end and open at its other and having an opening in one side substantially mid-way its ends, an adjustable closure in

the open end of the shell, a plate disposed 45 at each end of the shell, one of said plates being seated against the closed end of the shell and the other against said closure, an inwardly extending bearing stud on each of the plates, a carrying member, a pair of oppositely projecting pintles extending from the carrying member and disposed in said shell on each side of the intermediate opening therein, said carrying member being extended through said opening, the outer end of each pintle having a relatively deep socket 50 therein receiving the adjacent stud, and bearing elements disposed in each socket between the walls thereof and the peripheral surface of the studs.

2. In a steering mechanism of the class described, an elongated tubular bearing shell closed at one end and open at the other and having an opening in one side substantially mid-way its ends, said shell being split 55 transversely substantially mid-way said opening, a closure for the open end of the shell, an inwardly extended bearing stud projecting into the shell from adjacent each end thereof, a wheel spindle having one end portion disposed in the shell, the other portion being projected from the side opening therein, oppositely extending cylindrical 60 pintles connected with the first mentioned end of the spindle and rotatably disposed in the portions of the shell on opposite sides of said opening, the free end of each pintle having a relatively deep socket receiving 65 said studs, bearing elements disposed in said sockets and between the walls thereof and the periphery of said studs, and means rotatably supported by the projected portion of said spindle.

In testimony that I claim the foregoing I have hereunto set my hand at Milwaukee, 75 in the county of Milwaukee and State of Wisconsin.

RUDOLPH M. KANIK.
